United States Patent Office.

JOHN M. MAY, OF JANEVILLE, WISCONSIN.

Letters Patent No. 72,213, dated December 17, 1867.

IMPROVEMENT IN GATES.

The Schedule referred to in these Letters Patent and making part of the same.

TO ALL WHOM IT MAY CONCERN:

Be it known that I, JOHN M. MAY, of the city of Janesville, Rock county, and State of Wisconsin, have invented a new and useful Improvement in Operating Gates; and do hereby declare that the following is a full, clear, and exact description thereof, reference being had to the accompanying drawings, and to the letters of reference marked thereon.

My invention relates to operating gates that are opened and closed longitudinally, or in a parallel line with the fence, by sliding or by travelling on wheels, and kept perpendicular by means of friction-rollers or guides; also, in devices for unlatching and opening and latching and closing gates from a carriage, or when on horseback; also, in a latch, and device for operating a latch, so constructed and connected together that the latch may be operated with equal facility by hand from the ground, or by means of the device when in a vehicle or on horseback; also, in a peculiar roof or shelter for the protection of the working-mechanism.

The same letters of reference in each figure represent the same parts.

Figure 1 is an upright sectional drawing, a portion of the gate being broken away, showing a latch and a part of the device for opening and closing, and the mode of attaching the device to the gate.

Figure 2 is a top view of a part of the opening and closing-device.

Figure 3 is a sectional view at right angles with fig. 1, with an additional post.

Figure 4 is a sectional view at right angles with fig. 1, with additional posts and levers for operating the gate.

Figure 6 is a sectional detail drawing at right angles with fig. 1, showing a mode of connecting the rod that lifts the latch with the latch itself, so as to allow the latch to be operated without using the rod.

Figure 7 is a view of the rod connecting with an elbow-lever that lifts a latch.

Figure 8 is a view of the rear end of the gate-rail, showing a mode of attaching the rod to the rail.

Figure 9 is a cross-section at right angles with figs. 1 and 8, cut through from *h* to *i*; also gate-rails and a wheel and post.

Figure 10 is a sectional view at right angles with fig. 1, showing the manner of keeping the gate perpendicular.

A is the ground, in which the posts B are firmly set, while B¹ is a supplemental post, to which is attached a part of the working-mechanism. The principal post B may be made sufficiently long, and the post B¹ omitted; also, two posts, as B⁵, in figs. 3 and 4, may be used, and the gate and pendulum-lever M pass between them. The pendulum-lever M is pivoted to post B¹ or posts B⁵ in figs. 3 and 4, by bolt *a*, and is connected to the gate by means of bar N, and is hinged or pivoted in any suitable manner; but, if, in addition to opening and closing a gate, a latch is also to be used, I employ rod L, one end of which is connected to latch V, in fig. 1, or elbow V², to connect it with latch V¹ in fig. 7, the end being formed like a hook, the sides of which are parallel, as shown in fig. 6, or closed in the form of a link, as indicated by dotted lines in the same figure. This hook or link allows the projection C of the latch (or elbow V², as in fig. 7,) to move by hand back and forth inside the hook or link, as indicated by dotted lines in fig. 1. The handle *d* or knob-handle, as indicated by dotted lines at *d'*, may be used. When the latch is moved by rod L, to which is attached bar N, the part of rod L indicated by L' in figs. 1 and 9, the slot *e*, in fig. 8, allows the rod to move far enough to lift the latch from catch *r*, it being pivoted at *f*, when the continued longitudinal movement of the bar N moves the gate longitudinally on wheels, F, the friction-roller G keeping the gate perpendicular. The rod L is here placed underneath the rail C, and kept in line by means of hooks or pins, *g* and *g'*, and is protected from the weather and obstructions, as snow and ice, though it may be located in any place and in any manner on the rail that will serve in operating a gate. The rod L, to answer the purposes herein sought, is bent or formed, as indicated by L, L¹, L², and L³, in figs. 1, 6, 7, 8, and 9, and the angles or elbows are at *i* and *j* in figs. 1, 8, and 9. This rod may be made whole or in parts, and joined together in any suitable manner, or rod L may extend only from L² to pin *g'* and connect by a wire or cord to the latch; also, the part L¹, in figs. 1 and 9, serves as a bolt or pin to receive bar N in connecting the bar to the rail C, and moves in slot *e* as the gate is operated. The different parts of the gate are indicated by the letters C and D the rails, I the pickets, E the base, and E' the surbase or lower edge of the gate, which travels between friction-rollers G and pin H in figs. 9 and 10; but I do not confine myself to the above-described gate to be operated by means of my invention, as any gate that is moved longitudinally

may be used. The links P P connect by suitable joints to levers R R and with the arm O of the pendulum-lever M at α' . The pendulum-lever M is pivoted to post B¹, fig. 1, or B³ in figs. 3 and 4; and at b are the pivots by which levers R are attached to cross-head B⁴ in figs. 1 and 2, or to cross-head B⁵ in figs. 3 and 4. To the end of the long arm of levers R R are the pendent-rods S, attached by a loose link-joint. These levers have a length that brings the pendent-rods at a convenient distance from the gate to be reached from horseback or a carriage as the gate is approached. By drawing the rod downward, the pendulum-lever M is moved, first unlatching the gate and then opening it longitudinally, the wheels causing it to move easily, and when opened, the pendent-rod S, the levers R R, the links P P, the pendulum-lever M, with its arm O and the bar N, are moved to the position indicated by the dotted lines in fig. 1, which opens the gate. After the gate is passed, by raising the opposite pendent-rod S, the gate is closed and latched. In localities where a latch is not needed, the bar N may be connected direct to the gate by a pin or other suitable pivot, and the latch and rod be wholly omitted. P P are the bars that connect levers R R with rack O², which moves vertically in guides O³. The guides are sustained by any suitable framework, and the pendulum-lever M is moved by the rack and pinion as the pendent-rod S is raised or lowered, as before described.

I do not claim a roof or covering for mechanism used in operating a gate, except when constructed with open ends, substantially as described; nor do I claim a swinging lever, which I call a pendulum-lever, *per se*, but only when used in operating a gate that is moved longitudinally in opening and closing.

What I do claim as my invention, and desire to secure by Letters Patent, is—

1. Pendulum-lever M and bar N, operated by suitable mechanism, and combined with a gate that is moved longitudinally in opening and closing, substantially as described.
2. A gate-latch, combined with rod L, or its equivalent, when both are so constructed and connected together that the latch may be operated by hand or from a carriage, substantially as and for the purposes described.
3. Pendent-rods S S, levers R R, connecting-bars P P, arm O, pendulum-lever M, and bar N, when connected together and combined with a gate that is moved longitudinally in opening and closing, substantially as and for the purposes described.

JOHN M. MAY.
